UNITED STATES PATENT OFFICE.

ALBERT H. STEBBINS, OF LOS ANGELES, CALIFORNIA.

AIR CLASSIFIER.

Application filed September 24, 1926. Serial No. 137,596.

This invention relates to an air classifier and also to a series of air classifiers arranged one above the other in stacked relation to subject the materials to successive treatments.

It is frequently desirable in the treatment of ores and other materials to effect the separation of extremely fine dust-like particles from slightly larger dust-like particles, but such minute particles are extremely difficult to separate due to their tendency to remain suspended in the air employed in effecting their separation.

When the average particles being treated have the approximate size of the openings of a 100-mesh screen or larger, they may be separated fairly satisfactorily by a single air treatment, but when the particles to be treated are extremely small (say of a size to pass through a 500-mesh screen, if such fine screens were in use), then an air classification can be effected only by subjecting the particles repeatedly to the gentle separating action of slight air currents.

The present invention therefore contemplates a multiple treatment classifier that consists of a number of similar classifying receptacles that are connected in series so that the heavier particles pass from one receptacle to another and are subjected in each receptacle to gentle air currents that serve to carry off some of the finer particles.

One important feature of the present invention resides in the arrangement of the classifying receptacles one above the other in stacked relation so that the heavier particles flow by gravity from one receptacle to another.

Another feature of the invention resides in the simple construction whereby air under pressure is supplied to each receptacle from a single blast fan or other source of air supply, and also in the construction whereby a single suction conduit serves to remove the air and particles suspended therein from each receptacle.

Another feature of the invention resides in the construction of the individual classifying receptacles whereby the heavier particles are subjected to the lifting action of jets of air as they approach the discharge opening at the lower end of each receptacle. These jets of air serve to disengage from the larger particles and to carry upwardly the fine particles which tend to cling to such larger particles.

Still another feature of the invention resides in the construction whereby the air rising in each classifying receptacle is given a whirling movement that serves to throw the heavier particles outwardly against the walls of the receptacle.

Other features of the invention and novel combination of parts, in addition to the above, will be hereinafter described in connection with the accompanying drawings which illustrate good practical forms of the invention.

In the drawings—

Fig. 1 is a side elevation of a multiple treatment classifier constructed in accordance with the present invention;

Fig. 2 on an enlarged scale is a vertical sectional view through the upper portion of the multiple classifier of Fig. 1;

Fig. 3 on a still larger scale is a sectional view taken on the line 3—3 of Fig. 2;

Fig. 4 is a sectional view taken on the line 4—4 of Fig. 2;

Fig. 5 is a side elevation of a slightly different multiple treatment classifier from that of Fig. 1; and

Fig. 6 on an enlarged scale is a vertical sectional view through a modified construction for supplying air to the lower portion of a classifier.

The multiple treatment classifier of Fig. 1 is formed of a number of separate classifiers 10 which are arranged one above the other in stacked relation. Each of the classifiers 10, in the construction shown, is formed of a closed receptacle which preferably has the configuration best shown in Fig. 2, wherein it will be seen that the upper portion of each receptacle 10 has a relatively large annular portion, as indicated by 11, while the lower portion of each receptacle is conical in shape and has the inclined walls 12 which converge towards their lower end and serve to direct the heavier particles into the discharge opening 13 at the lower end of a receptacle. The upper end of each receptacle is closed by a cover 14.

The construction of the receptacles 10 is such that the heavier materials that settle in one receptacle will slide down the inclined walls 12 through the discharge opening 13 into the next receptacle, so that the heaviest materials pass successively through any desired number of receptacles 12, and in each of these receptacles they are subjected to the action of rising currents of air which

serve to gradually remove from the heavier particles the lighter particles that tend to cling to the heavier particles.

As above indicated an important feature 5 of the present invention resides in the construction whereby the heavier particles that settle in a classifier 10 must travel across a number of air jets near the lower end of the receptacle before they can escape 10 through the discharge opening 13. In the construction shown in Figs. 1, 2 and 3, these air jets are produced by giving the lower portion of each receptacle 10 the stepped construction best shown in Fig. 2 wherein 15 it will be seen that such stepped portion consists of the annular upright portions 15 that are connected by the inclined portions 16. Each annular portion 15 has a number of slots or apertures 17 formed through its 20 wall and these slots are provided with the inwardly extending lips 18, the arrangement being such that the air passing inwardly through the slots 17 is given a rotative movement as it moves upwardly 25 within the receptacle. The upper ring portions 15 are larger in diameter than the lower ring portions and the upper ring portions are therefore provided with more apertures 17 than the lower or small rings 15. 30 In order to force air inwardly through the apertures 17, a casing 19 is provided about the stepped portion of each receptacle 10, and air under pressure is supplied to each casing 19 by a tangentially disposed 35 pipe 20 that leads from a conduit 21 disposed alongside the stack of receptacles. The conduit 21 preferably decreases in diameter in an upward direction to accommodate the volume of air passing through different portions of the conduit and air under pressure may be supplied to this conduit by a blast fan 22 that is connected by a pipe 23 to the conduit.

Since the receptacles 10 increase in size 45 in an upward direction, the air rising in the receptacles is permitted to expand and spread out laterally as it rises, with the result that its lifting effect upon the particles suspended in the air decreases as the air 50 approaches the upper part of a receptacle. This gives the heavier particles an opportunity to settle upon the inclined walls 12, and the slope of these walls is sufficiently 55 steep to cause the materials to slide down the walls into the vicinity of the apertures 17 for further treatment. In this manner the particles may be treated a number of times in any one of the receptacles before they finally escape through the opening 13 60 past the air jets, or are carried upwardly out of the receptacle through the air discharge outlet 24.

The whirling movement imparted to the air within the receptacles by the construction of the apertures 17 described serves to

spread the air out in the receptacles and also to throw the particles outwardly by centrifugal force against the walls 12 to slide down these inclined walls.

Each of the receptacles 10 is preferably 70 connected to an air exhaust conduit 25 disposed alongside the stack of receptacles and this conduit preferably increases in diameter in an upward direction to accommodate the increased volume of air drawn into the 75 same, and the upper end of this conduit may be connected to a suction dust extractor 26. The heavier particles that may be carried by the air into the conduit 25 are subjected to a settling or retreatment action 80 therein, and the retreatment of the particles in this conduit is promoted by giving a rotative movement to the air therein which helps to work the heavier particles outwardly against the walls of the conduit. The desired rotative movement is imparted to the air within the conduit 25 by constructing the connecting pipes 27 as best shown in Fig. 4 wherein it will be seen that each pipe 27 directs its air more or less tangentially 90 into the suction conduit. The particles that settle in the conduit 25 pass through a small pipe 28 into a closed receptacle 29.

The materials to be treated may be delivered to the uppermost receptacle 10 from a feed hopper 30, and in order to secure a uniform flow of materials from the hopper, a rotating feed disk 31 may be provided which may be rotated by a belt engaging the pulley 32. In order to spread the materials out in the uppermost receptacle they may be delivered upon the cone deflector 33 and around which is placed the annular wall 34 arranged to prevent the rising air within the receptacle from reaching the 100 feed pipe 35.

When the materials being treated contain exceptionally fine particles, these fine particles may tend to pack or cling to the side walls of the classifiers. It may therefore 110 be desirable to make the walls 36 of the receptacles near the upper end of the multiple classifier steeper than the walls of the lower receptacles, as shown in the modified construction of Fig. 5. As soon as the extremely fine particles have been removed 115 the remaining particles will have a less tendency to cling to the side walls 36 so that the walls of the lower receptacles do not require such a steep slope.

In Fig. 6 is shown a somewhat different construction for introducing jets of air into the lower portion of a receptacle 10 about the discharge pipe. In this construction the vertical walls 37 are not perforated, but 125 a large number of apertures 38 are formed in the inclined walls 39.

As a result of the multiple classifier construction described, any desired number of individual classifiers may be arranged in 130

- stacked relation one above the other, and since the individual classifiers may be relatively small, a large number of these classifiers (say fifty or more) may be assembled 5 one above the other in stacked relation without producing an excessively tall tower. This large number of classifiers may be operated from one air blast pipe and from one air exhaust pipe, and may be operated from 10 a single feed hopper. The volume of air required to operate a large number of the classifiers will be relatively small because of the necessity of employing gentle air currents in separating fine dust-like particles. 15 The heavier materials as they pass downwardly through the different classifiers are subjected time and time again to the action of rising currents of air that gently carry off the lighter particles. The lowermost receptacle 10 may be discharged into the closed bin 40.
- What is claimed is:—
1. An air classifier comprising in combination, a closed receptacle having an air discharge opening near its upper end and side walls that converge downwardly towards a central opening at its lower end through which the heavier materials are discharged, means for introducing air under 25 pressure into the lower portion of the receptacle at a multiplicity of points around the material discharge opening and including an apertured surface having inclined apertures formed to impart a rotating spiral 30 movement to the air rising in the receptacle, and means for delivering the materials to be treated into the upper part of the receptacle so that the heavier particles are carried outwardly by the rotating air to slide down the 35 side walls of the receptacle across the air inlet openings into the material discharge opening while the light particles are carried by the air upwardly through the air discharge opening.
  - 45 2. An air classifier, comprising in combination, a closed receptacle having a central opening at its lower end and tapered downwardly converging walls that direct materials into said opening and also having an air discharge opening near its upper end, the lower end of the receptacle being provided with a multiplicity of air inlet apertures disposed to deliver currents of air through the particles that slide down the 50 walls of the receptacle toward the material discharge opening, said apertures being constructed to impart a spiral movement to the air passing through them to throw the heavier particles outwardly by centrifugal force, 55 a closed casing surrounding the apertured portion of the receptacle, and disposed out of the path of the falling materials, means for forcing air into said casing to deliver air under pressure to said apertures, and 60 means for delivering the materials to be 65 treated into the upper part of the receptacle so that the heavier particles settle within the receptacle in opposition to the rising air currents while the lighter particles are carried by the air through the air discharge opening. 70
  3. An air classifier, comprising in combination, a conical shaped receptacle having a material discharge opening at its lower end and an air discharge opening near its upper end, said receptacle having downwardly converging side walls and a stepped annular portion near its lower end that surrounds the material discharge opening and the stepped portion being provided with apertured areas separated by unapertured areas, 75 a closure for the upper end of the receptacle, means for delivering the materials to be treated into the upper portion of the receptacle, and means for directing air through said apertures to produce rising air currents in the receptacle to carry the lighter particles out through said air discharge opening while the heavier particles slide down the side walls across the apertured area. 80
  4. A multiple treatment classifier, comprising in combination, a series of closed classifying receptacles disposed one above the other in stacked relation and each receptacle having downwardly converging side walls that direct the materials that settle in one receptacle into the next lower receptacle for further treatment, means for introducing air into the lower portion of each receptacle at a number of points about its converging 85 walls to produce rising air currents that carry the lighter particles upwardly toward the upper end of each receptacle, and means for removing the air and lighter particles from each receptacle so that the separating air does not pass from one receptacle to the next. 90
  5. A multiple treatment classifier, comprising in combination, a series of closed classifying receptacles disposed one above the other in stacked relation and constructed and arranged so that the materials that settle in one receptacle flow by gravity into the next lower receptacle for further treatment, means for introducing air into the lower portion of each receptacle to produce rising air currents that carry the lighter particles being treated toward the upper end of the receptacle, and means for removing the air and lighter particles from each receptacle so that the separating air does not pass from one receptacle to the other. 100
  6. A multiple treatment classifier, comprising in combination, a series of similar classifying receptacles disposed one above the other in stacked relation and constructed and arranged so that the materials that settle in one receptacle flow by gravity into the next receptacle for further treatment, a suction conduit for carrying off from the receptacles 105
  7. A multiple treatment classifier, comprising in combination, a series of closed classifying receptacles disposed one above the other in stacked relation and constructed and arranged so that the materials that settle in one receptacle flow by gravity into the next receptacle for further treatment, a suction conduit for carrying off from the receptacles 110
  8. A multiple treatment classifier, comprising in combination, a series of closed classifying receptacles disposed one above the other in stacked relation and constructed and arranged so that the materials that settle in one receptacle flow by gravity into the next receptacle for further treatment, a suction conduit for carrying off from the receptacles 115
  9. A multiple treatment classifier, comprising in combination, a series of closed classifying receptacles disposed one above the other in stacked relation and constructed and arranged so that the materials that settle in one receptacle flow by gravity into the next receptacle for further treatment, a suction conduit for carrying off from the receptacles 120
  10. A multiple treatment classifier, comprising in combination, a series of closed classifying receptacles disposed one above the other in stacked relation and constructed and arranged so that the materials that settle in one receptacle flow by gravity into the next receptacle for further treatment, a suction conduit for carrying off from the receptacles 125
  11. A multiple treatment classifier, comprising in combination, a series of closed classifying receptacles disposed one above the other in stacked relation and constructed and arranged so that the materials that settle in one receptacle flow by gravity into the next receptacle for further treatment, a suction conduit for carrying off from the receptacles 130

- the air and the lighter particles suspended in the air, a connection between each receptacle and said suction conduit for removing the air without causing it to pass from one receptacle to the next, and a blast pipe having connections for delivering air under pressure into the lower portion of each receptacle to produce rising air currents within the receptacles.
- 10 7. A multiple treatment classifier, comprising in combination, a series of classifying receptacles disposed one above the other in stacked relation and each having downwardly converging side walls adapted to direct the materials that settle in one receptacle into the upper portion of the next lower receptacle for further treatment, means for introducing jets of air through the converging walls of each receptacle so that the particles sliding down the side walls are directed across the air jets, and means for removing from the upper part of each receptacle the air and light materials suspended therein so that the separating air does not pass from one receptacle to the next.
- 15 8. A multiple treatment classifier, comprising in combination, a series of classifying receptacles disposed one above the other and constructed and arranged so that the larger particles that settle in one receptacle flow by gravity into the next receptacle for further treatment, means for delivering clean air under pressure into the lower portion of each receptacle to produce rising air currents that pick up the lighter particles, and means for removing from each receptacle the air and the lighter particles carried by the air so that the separating air does not pass from one receptacle to another.
- 20 9. A multiple treatment classifier, comprising in combination, a series of classifying receptacles disposed one above the other in stacked relation and arranged so that the heavier particles that settle in one receptacle are directed into the next lower receptacle for further treatment, each receptacle being provided with a converging lower end having a central opening through which the heavier particles pass into the next receptacle, means for introducing rising currents of air into the receptacle around said discharge opening to remove the lighter particles from the heavier particles, and means for removing from the upper portion of each receptacle the air and lighter particles suspended in the air so that the air is supplied to and exhausted from each receptacle independently of the other receptacles.
- 25 10. A multiple treatment classifier, comprising in combination, a series of classifying receptacles disposed one above the other and arranged so that the heavier particles that settle in one receptacle flow by gravity into the next receptacle for further treatment, each receptacle being provided with a con-
- verging lower end having a central opening through which the heavier particles pass into the next receptacle and having a series of air apertures formed in the receptacle about said opening, a casing surrounding the apertured portion of each receptacle, means for forcing air into each casing to form jets of air entering the receptacles through said apertures, and means for removing from the upper part of each receptacle independently of the other receptacles the air and the lighter particles suspended in the air.
- 30 11. A multiple treatment classifier, comprising in combination, a series of classifying receptacles disposed one above the other and arranged so that the heavier particles that settle in one receptacle flow by gravity into the next receptacle for further treatment, means for introducing air into the lower portion of each receptacle with an upward spiral movement that causes it to spread out and throw the heavier particles against the walls of the receptacle, and means for removing from the upper part of each receptacle independently of the other receptacles the air and the lighter particles suspended in the air.
- 35 12. A multiple treatment classifier, comprising in combination, a series of classifying receptacles disposed one above the other in stacked relation and arranged so that the heavier particles that settle in one receptacle flow by gravity into the next lower receptacle, means for introducing air into the lower portion of each receptacle to rise therein so that the materials within each receptacle are subjected to the separating action of rising air currents, a vertical conduit disposed adjacent the stack of receptacles and in which the finer materials that pass from the receptacles into the stack are subjected to a reclassifying action, means for exhausting air from the upper end of the conduit, and a pipe between each receptacle and said conduit and arranged to deliver the air passing through the pipe approximately tangentially into the conduit to impart a rotating movement to the volume of air in the conduit.
- 40 13. A multiple treatment classifier, comprising in combination, a series of closed classifying receptacles disposed one above the other in stacked relation and arranged so that the heavier particles that settle in one receptacle will flow by gravity into the next lower receptacle, means for supplying air under pressure to each receptacle, comprising a conduit extending lengthwise of the stack and provided with branch pipes for delivering air into the lower portion of each receptacle to rise therein so that the materials within each receptacle are subjected to the separating action of rising air currents, and means for removing air from each receptacle without causing the air to pass from

one receptacle to the next; comprising a second conduit extending lengthwise of the stack and provided with branch pipes leading from the upper portion of each receptacle to the conduit.

14. A multiple treatment classifier, comprising in combination, a stack formed of a large number of small classifying receptacles disposed one above the other and arranged so that the heavier particles will flow by gravity from one receptacle to the next,

an air supply conduit extending lengthwise of said stack and provided with branch pipes leading into the lower end of each receptacle, an air exhaust pipe extending lengthwise of said stack and provided with branch pipes for conducting air from the upper portion of each receptacle, and means for exhausting air from the last mentioned pipe.

In testimony whereof, I have signed my name to this specification.

ALBERT H. STEBBINS.
